[57] CLAIM

The ornamental design for a stand for light fixture or similar article, as shown and described.

DESCRIPTION

FIG. 1 is a side elevational view of a stand for light fixture or similar article having my new design, the side opposite being a mirror image thereof;

FIG. 2 is a top plan view of FIG. 1;

FIG. 3 is a front elevational view of FIG. 1;

FIG. 4 is a side elevational view of a second embodiment of the design of FIG. 1, the side opposite being a mirror image thereof;

FIG. 5 is a top plan view of FIG. 4;

FIG. 6 is a front elevational view of FIG. 4;

FIG. 7 is a side elevational view of a third embodiment of the design of FIG. 1, the side opposite being a mirror image thereof;

FIG. 8 is a top plan view of FIG. 7;

FIG. 9 is a front elevational view of FIG. 7;

FIG. 10 is a side elevational view of a fourth embodiment of the design of FIG. 1, the side opposite being a mirror image thereof;

FIG. 11 is a top plan view of FIG. 10;

FIG. 12 is a front elevational view of FIG. 10;

FIG. 13 is a side elevational view of a fifth embodiment of the design of FIG. 1, the side opposite being a mirror image thereof;

FIG. 14 is a top plan view of FIG. 13;

FIG. 15 is a front elevational view of FIG. 13;

FIG. 16 is a side elevational view of a sixth embodiment of the design of FIG. 1, the side opposite being a mirror image thereof;

FIG. 17 is a top plan view of FIG. 16;

FIG. 18 is a front elevational view of FIG. 16;

FIG. 19 is a side elevational view of a seventh embodiment of the design of FIG. 1, the side opposite being a mirror image thereof;

FIG. 20 is a top plan view of FIG. 19;

FIG. 21 is a front elevational view of FIG. 19;

FIG. 22 is a side elevational view of an eighth embodiment of the design of FIG. 1, the side opposite being a mirror image thereof;

FIG. 23 is a top plan view of FIG. 22; and

FIG. 24 is a front elevational view of FIG. 22.
